Fig. 6.

FIG. 1 is a top plan view of a firearms recoil pad for firearms, showing my new design;

FIG. 2 is a side view of FIG. 1, the opposite side being the same;

FIG. 3 is a left end elevation of FIG. 1;

FIG. 4 is a right end elevation of FIG. 1;

FIG. 5 is an enlarged fragmentary detail view of the design pattern; and

FIG. 6 is an enlarged cross-section taken on line 6—6 of FIG. 5.

The dominant features of the design reside in the solid line portions.

I claim:

The ornamental design for a firearms recoil pad, substantially as shown and described.
